United States Patent Office

Des. 192,521
Patented Apr. 3, 1962

192,521

FIELD CULTIVATOR

Glenn E. Frager, Hutchinson, Kans., assignor to Krause Corporation, Inc., Hutchinson, Kans., a corporation of Kansas

Filed July 17, 1961, Ser. No. 65,930

Term of patent 14 years

(Cl. D39—1)

Fig. 1.

Fig. 2.

FIG. 1 is a top plan view of a field cultivator showing my new design;

FIG. 2 is a side elevational view thereof; and

FIG. 3 is an enlarged front perspective view of a field cultivator.

The dominant features of my design reside in the full line portions of the drawing.

I claim:

The ornamental design for a field cultivator, as shown and described.
